UNITED STATES PATENT OFFICE

153,868

DESIGN FOR A FINGER RING OR KINDRED ARTICLE

James B. Fishburne, Norfolk, Va.

Application March 4, 1948, Serial No. 144,895

Term of patent 3½ years

(Cl. D45—10)

To all whom it may concern:

Be it known that I, James B. Fishburne, a citizen of the United States, residing at Norfolk, in the county of Norfolk and State of Virginia, have invented a new, original, and ornamental Design for a Finger Ring or Kindred Article, of which the following is a specification, reference being had to the accompanying drawing, forming part thereof.

The figure of the drawing is a view in perspective of a finger ring or kindred article embodying the new design, both sides being in duplicate and the rope-like ornamentation along the edges tapering toward the rear and vanishing as indicated on the drawing.

I claim:

The ornamental design for a finger ring or kindred article, substantially as shown and described.

JAMES B. FISHBURNE.
